C. A. ORR.
HYDROCARBON BURNER APPARATUS.
APPLICATION FILED DEC. 10, 1919.

1,415,384.

Patented May 9, 1922.

UNITED STATES PATENT OFFICE.

CARLETON A. ORR, OF PUEBLO, COLORADO, ASSIGNOR TO THE BAKER STEAM MOTOR CAR AND MANUFACTURING CO., INC., OF PUEBLO, COLORADO.

HYDROCARBON-BURNER APPARATUS.

1,415,384.

Specification of Letters Patent. Patented May 9, 1922.

Application filed December 10, 1919. Serial No. 343,887.

To all whom it may concern:

Be it known that I, CARLETON A. ORR, a citizen of the United States, residing at Pueblo, in the county of Pueblo and State 5 of Colorado, have invented certain new and useful Improvements in Hydrocarbon-Burner Apparatus; and I do hereby declare the following to be a full, clear, and exact description of the invention, such as will enable others skilled in the art to which it 10 pertains to make and use the same.

This invention relates to hydrocarbon burners, the improvements being more particularly intended for use in connection with a 15 water boiler or steam generator such as used in steam automobiles, although the improvements can be used in hydrocarbon burners generally for which they are suited.

One object of the invention is the provision of novel means for mixing the air and fuel, and to thoroughly atomize the fuel in so doing, whereby the mixture is quickly ignited and the combustion thorough.

Another object is the provision of a hydrocarbon burner apparatus using a fan or blower for furnishing a copious supply of air under pressure, and novel means whereby such blower is operated automatically to supply air when fuel is delivered, thereby 30 simultaneously establishing the supply of air and fuel and likewise simultaneously cutting off such supply, under the control of an automatic pressure valve or the like.

A still further object is the provision of 35 such an apparatus including a spark plug or igniter for igniting the fuel, and automatic means for bringing such igniter into operation when the flow of fuel and air is started and for automatically cutting out such igniter after a short interval of time after the fuel is lighted, thereby causing the simultaneous flow of air and fuel and the lighting of the mixture, in order that the burner can be started instantly.

With the foregoing and other objects in view, which will be apparent as the description proceeds, the invention resides in the construction and arrangement of parts hereinafter described and claimed, it being

understood that changes can be made within the scope of what is claimed without departing from the spirit of the invention.

Figure 1 is a diagrammatical view of the apparatus.

Fig. 2 is a fragmentary detail view showing a modification.

The apparatus is illustrated as designed for use on a steam motor vehicle, but can be used for other kindred purposes, and, as shown, the apparatus includes a steam generator or boiler 1 having the burner pan or bowl 2 at the bottom (which may be lined with asbestos or other refractory material) and the smoke cap 3 at the top from which the chimney 4 extends for the outlet of the 65 product of combustion. The fuel is delivered into the burner pan 2 at one side through any suitable nozzle 5 from a fuel tank 6, and the apparatus will burn kerosene, gasoline, alcohol, crude oil and other 70 fuels, successfully. A pipe 7 leads from the tank 6 and has a manual controlling valve 8 for establishing and stopping the flow of fuel manually, and said pipe 7 leads to an automatic pressure valve 9, from 75 which the fuel supply pipe 10 leads to the nozzle 5. The valve 9 has connected thereto a steam pipe 11 leading from the boiler 1, whereby the valve 9 is automatically opened and closed by a reduction and increase in 80 pressure, respectively, whereby the fuel can flow past the valve 9 when the pressure is low and will be restricted or checked in its flow by the increase in steam pressure.

The fuel is maintained under pressure in 85 the tank 6 so as to flow under pressure to and through the nozzle 5, and, for this purpose, the compressed air tank 12 is provided, and may be disposed next to the fuel tank 6. The tanks 6 and 12 have the respective pressure gages 13 and 14, the air in the tank 12 being under high pressure, whereas the pressure in the tank 6 is comparatively low. The tank 12 has a valve and hose connection 15 for convenience in pumping air into said 90 tank at intervals, and the tank 6 has a filling neck 16 through which the fuel is poured into the tank. The air is delivered from

- the tank 12 into the tank 6 by means of an air pipe 17 leading from the tank 12 and preferably connected to the neck 16. A pressure reducing valve 18 is disposed in the pipe 17 for the passage of air into the fuel tank 6, but restricting such flow so as to maintain a predetermined low pressure in the tank 6. The neck 16 has a valve chamber 19 therein into which the air flows from the pipe 17, and a check valve 20 is disposed in the chamber 19, being normally held open by the cap 21 which is removably secured on the neck 16, whereby when said cap is removed for filling the tank 6, the valve 20 is released so as to prevent the discharge and waste of air from the tank 12. In this manner, when the cap 21 is removed for filling the fuel tank 6, the flow of air from the tank 12 is automatically stopped, and such flow will be reestablished when the cap 21 is again applied to the neck 16. The valves 8 and 9 being open, will deliver the fuel under pressure from the tank 6 to the delivery nozzle 5.
25. An air fan or blower 22 is used for supplying an abundant flow of air to maintain combustion and to create a forced draft through the boiler and down the chimney 4. The air conduit 23 extends from the blower 22 and delivers the air into the burner pan 2 opposite to the fuel nozzle 5, whereby the inflowing streams of fuel and air are directed toward one another in opposition, both the air and fuel being under pressure. The fuel is sprayed from the nozzle 5 and the air and fuel impinging against one another, will result in the particles of fuel being broken up into a fine mist or vapor, similar to the action of the wind when striking water delivered from a hose nozzle, which causes the drops of water to be broken into a fine mist. In this way, the fuel is thoroughly atomized and mixed with the air, and can be lighted 40 instantly without using a carburetor, vaporizer, generator or similar appliance. This simplifies the burner by eliminating burner plates, vaporizer, priming burner, etc. With the present arrangement, the fuel and air are delivered into the burner chamber from opposite directions and this will vaporize the fuel and mix the fuel and air thoroughly. It is preferable to provide a set of vanes 24 within the delivery portion of the air conduit or pipe 23, which are twisted into helical or spiral form whereby to give the stream of air a whirling motion, thereby enhancing the vaporization of the fuel and mixture of fuel and air.
50. The operating means of the blower 22 embodies an electric motor 25 disposed in an electrical circuit 26 having the battery 27 or other source of electrical energy, and a hydraulic or pressure switch 28 is disposed in said circuit and has connected thereto a branch pipe 29 leading from the fuel supply pipe 10 at that side of the valve 9 opposite to the fuel tank 6. Any suitable hydraulic or pressure switch can be used, whereby to normally open the circuit when the pressure is low, and to automatically close the circuit when the pressure is increased. Thus, when the valves 8 and 9 are open, the pressure of the fuel from the tank 6 will close the switch 28, in order that when the fuel is delivered from the nozzle 5, the motor circuit will be instantly closed and the blower 22 operated to furnish air at the same time that fuel is discharged into the burner. Conversely, when the steam pressure closes the valve 9, to shut off the flow of fuel, the reduction in pressure will automatically open the valve 8, so as to stop the blower at the instant that the discharge of fuel is stopped. The fuel and air are thus automatically and simultaneously delivered into the burner and shut off according to pressure.
55. In order to ignite the fuel when the flow of fuel and air is started, a conductor 30 is branched from the circuit 26 as a shunt parallel with the motor 25, and has connected therein an electric automatic cut off time switch 31 of any suitable kind, and the conductor 30 leads through the primary coil of an ordinary or suitable spark coil 32, the switch 31 operating to open the spark coil circuit after the current flows for a short interval. The switch 31 is normally closed, so that when the switch 28 is closed, the current will flow through both the motor 25 and spark coil 32, but the switch 31 will open the spark coil circuit after a short interval whereas the motor 25 continues to operate. The secondary circuit 33 of the spark coil 32 is connected to the spark plug or igniter 34, and the spark coil 32, will as usual, induce a high potential current in the circuit 33 when the current flows through the primary conductor or circuit 30, which will result in the igniter 34 igniting the fuel, it being noted that the igniter is energized at the instant the fuel is delivered into the burner and the flow of air started.
60. In operation, supposing that the valve 8 is closed so that the apparatus is at rest, the valve 9 being opened due to the reduction in steam pressure in the boiler. The valve 8 being closed, will reduce the pressure in the fuel supply pipe beyond such valve so that the switch 28 will remain open. To start the burner, the valve 8 is opened, and the fuel will flow past said valve 8 and valve 9 through the pipe 10 and nozzle 5, and at the same time, the switch 28 is closed by the fuel pressure, thereby closing the motor circuit and starting the blower 22. The air is thus supplied at the same time that the flow of fuel is started, and, furthermore, the closure of the switch 28 enables

the electric current to flow past the switch 31 thereby energizing the spark coil 32 which will result in the igniter 34 igniting the fuel immediately upon entering the burner chamber. The igniter 34 is stopped after a short interval, by the automatic opening of the switch 31, and the ignition device is thus brought to rest, as it is no longer needed after the fuel is lighted, being only brought into operation when the flow of fuel and air is first established after having been cut down. When the steam pressure increases to a point for which the valve 9 has been adjusted, said valve will be closed, thereby shutting off the flow of fuel and the switch 28 will then open to stop the blower. When the pressure of steam reduces, the valve 9 will open, thereby reestablishing the flow of fuel, closing the switch 28 to start the blower and, at the same time, energizing the igniter 34, the same as before.

In the modification shown in Fig. 2, the fuel nozzle 5' is located centrally of the vanes 24 within the air conduit 23, whereby the air and fuel enter the burner chamber from the same direction, and such vanes will whirl the air around the discharging stream of fuel for thoroughly atomizing and mixing the fuel. This arrangement, however, will not have the advantage of the opposing streams of air and fuel striking one another as in the preferred form.

Having thus described the invention, what is claimed as new is:—

1. A hydrocarbon burner comprising a combustion chamber, and means for discharging fuel and air under pressure independently into said chamber from opposite directions toward one another so that the independent streams of fuel and air impinge against one another within said chamber.

2. A hydrocarbon burner comprising a combustion chamber, independent fuel and air nozzles directed into said chamber from opposite directions toward one another, and means for supplying fuel and air under pressure independently to said fuel and air nozzles, respectively, so that the fuel and air enter the chamber independently and impinge against one another within said chamber.

3. A hydrocarbon burner comprising a combustion chamber, means for independently discharging fuel and air under pressure into said chamber from opposite directions so that the independent streams of fuel and air impinge against one another within said chamber, and means for whirling the stream of air prior to its contact with the fuel stream.

4. A hydrocarbon burner apparatus embodying fuel supplying means, controlling means therefor, a blower for supplying air,

means for operating the blower, and means controlling such operating means and in turn controlled by the fuel supplying means to automatically start and stop the blower operating means when the fuel is supplied and cut off.

5. A hydrocarbon burner apparatus embodying a fuel supplying pipe, a controlling valve for controlling the flow of fuel through said pipe, a blower for supplying air, means for operating said blower, and pressure-operated means controlled by fuel pressure in said pipe and controlling the operation of said operating means to start and stop it according to fuel pressure.

6. A hydrocarbon burner apparatus comprising fuel supplying means, controlling means for said means to control the flow of fuel, a blower for supplying air, an electric motor for operating the blower, and a pressure operated switch controlling the circuit of the motor and connected to said fuel supplying means to be operated by fuel pressure.

7. A hydrocarbon burner apparatus embodying a fuel tank, a fuel supply pipe for delivering fuel from said tank, an automatic pressure valve controlling the flow of fuel from said tank into said pipe, a manual controlling valve between said automatic valve and tank, a blower for supplying air, an electric motor for operating said blower, and a pressure-operated switch controlling the circuit of said motor and connected to said pipe at that side of the automatic valve opposite to the fuel tank.

8. A hydrocarbon burner apparatus embodying a fuel supply pipe, controlling means for controlling the flow of fuel, a blower for supplying air, means for operating said blower, an igniter for igniting the fuel, means controlling said operating means and igniter and controlled by fuel pressure in said pipe for bringing said operating means and igniter into operation by fuel pressure, and means for automatically rendering the igniter inoperative after an interval of time.

9. A hydrocarbon burner apparatus embodying a fuel supply pipe, a controlling valve for controlling the flow of fuel through said pipe, an igniter for igniting the fuel, an electrical circuit for energizing said igniter, a pressure-operated switch for closing said circuit and connected to said pipe to be operated by fuel pressure for closing said circuit, and an automatic electric cut-off time switch in said circuit to open same after an interval of time.

10. A hydrocarbon burner apparatus embodying a fuel tank, a fuel supply pipe for delivering fuel from said tank, a controlling valve for controlling the flow of fuel from said tank through said pipe, a blower for supplying air, an electric motor for operating said blower, electrical ignition means for

igniting the fuel, a pressure-operated switch controlling the circuits of both said ignition means and motor and connected to said pipe for closing said circuits by fuel pressure, and a cut-off time switch in the circuit of said ignition means for opening said circuit after an interval of time.

In testimony whereof I have signed my name to this specification in the presence of two subscribing witnesses.
